CLAIM

The ornamental design for a serrated light engine and circuit board, as shown and described.

DESCRIPTION

FIG. 1 is a top plan view of a first embodiment of a serrated light engine and circuit board, showing our new design, the bottom view being a mirror image thereof;

FIG. 2 is a left perspective view thereof;

FIG. 3 is a right perspective view thereof;

FIG. 4 is a side view thereof;

FIG. 5 is a front view thereof;

FIG. 6 is a top plan view of a second embodiment of a serrated light engine and circuit board, showing our new design, the bottom view being a mirror image thereof;

FIG. 7 is a left perspective view thereof; and,

FIG. 8 is a right perspective view thereof.

The broken line disclosure is for environmental purposes only and does not form a part of the claimed design.

All surfaces not shown form no part of the claimed design.
